DESIGN FOR WALL-PAPER.

Design No. 12,499, dated September 27, 1881.

UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,499, dated September 27, 1881.

Application filed August 25, 1881. Term of patent 3 $\frac{1}{4}$ years.

To all whom it may concern:

Be it known that I, EDUARD LEISSNÈR, of New York, in the county and State of New York, have invented a new and original Design for Wall-Paper, of which the following is a specification.

This invention relates to a new and original design for wall-paper and similar fabrics; and it consists in the novel grouping and configuration of parts, hereinafter more fully described.

The accompanying photograph illustrates a face view of a wall-paper having my new design.

15 Four bars or stripes pass over the background of this wall-paper and form, by their bends and directions, the alternating upright and horizontal hexagons D and E. The upright

hexagons contain each a stem, h, with leaves growing therefrom, and this stem projects from each upright hexagon D into the horizontal hexagon E next above, where it terminates into forked leaves and tendrils, as shown. The spaces between the hexagons are filled with scrolls f.

20 I claim—

1. The design for wall-paper having stripes formed into alternating upright and horizontal hexagons D E, substantially as shown.

2. The design for wall-paper, consisting of 25 the figures D E and ornaments f h, substantially as shown.

EDUARD LEISSNÈR.
